COMBINED VALET STAND AND GARMENT HANGER

Laurence W. Van Dusen, Escondido, Calif., assignor to
Mission Industries, Escondido, Calif., a corporation of
California

Filed Nov. 7, 1962, Ser. No. 72,423

Term of patent 14 years

(Cl. D33—8)

FIG. 1.

FIG. 2.

FIG. 3.

FIG. 4.

FIG. 5.

FIGURE 1 is a perspective view illustrating my novel design for combined valet stand and garment hanger, one of the garment-supporting members being shown in the removed position, a portion of the wire member of the other garment-supporting member being broken away for convenience of illustration.

FIGURE 2 is a front elevation thereof.

FIGURE 3 is a side elevation thereof.

FIGURE 4 is a top plan view thereof.

FIGURE 5 is a bottom plan view thereof.

The design is characterized by the combination disclosed of the paired hanger members in association with the tray element and the tapered side frames, all as shown.

I claim:

The ornamental design for combined valet stand and garment hanger, substantially as shown and described.
